FURNITURE FOOT

Filed June 24, 1929

Inventor: James E. Bales,
By Cheever, Cox + Moore: Atty.

UNITED STATES PATENT OFFICE

JAMES E. BALES, OF AURORA, ILLINOIS, ASSIGNOR TO LYON METAL PRODUCTS, INCORPORATED, OF AURORA, ILLINOIS, A CORPORATION OF ILLINOIS

FURNITURE FOOT

Application filed June 24, 1929. Serial No. 373,092.

This invention relates to a foot which is attached to articles of furniture, and it relates particularly to a rubber foot for chairs.

The object of the invention is to provide a new and novel foot for chairs and the like, which are provided with tubular or other hollow legs.

Another object is to provide a rubber foot for chairs which has a portion thereof extending up into the leg of the chair, and which has means provided for securely maintaining the foot in position.

A further object is to provide a rubber foot for hollow chair legs and the like, which has a knob or head which abuts the end of the leg, which has a portion integral with the knob extending into the leg, and which is provided with tightening means for compressing the foot so that it will swell tightly inside of the hollow leg and hold the foot in place to prevent it from being accidentally removed or lost.

Other objects and advantages will appear throughout the progress of the specification.

The invention comprises in general a rubber foot which has a knob and an elongated body portion. A hole is provided in the foot throughout its entire length and receives a bolt for compressing and swelling the foot.

The hole has a larger bore at its outer end in the knob portion, and a washer is embedded in the knob to provide a bearing for the bolt head. A washer is arranged on the bolt at the inner end of the foot, and it has struck up portions thereon to hold a nut and prevent it from turning during tightening of the bolt.

The accompanying drawings illustrate a selected embodiment of the invention and the views therein are as follows:

Fig. 1 is a perspective view of a chair having the improved rubber foot applied to each leg thereof.

Fig. 2 is a detail view, partly in section, showing the rubber foot applied to a tubular chair leg.

Fig. 3 is a sectional plan view on the line 3-3 of Fig. 2.

Fig. 4 is a top plan view of the nut holding washer.

Fig. 5 is a sectional view on the line 5-5 of Fig. 4.

Fig. 6 is a sectional view of the rubber foot.

Fig. 7 is a top plan view thereof.

Referring to the drawings, 10 designates any type of chair to which the invention may be adapted. The rear legs are pivoted to the front legs and stretchers 12 and 13 are connected to the front and rear legs respectively. The chair has a back 14 and a hinged seat 15, so that it may be folded up and stored away when not in use.

The legs 11 are substantially tubular in cross section and each leg is provided with a rubber foot 16 to prevent marring the floor and to prevent the chair from sliding or creeping.

The foot 16 is preferably made of soft rubber, although it may be made from other soft yieldable material, if desired. The foot has a knob 17 and a body portion 18 which tapers slightly toward its inner end. The knob is larger in diameter than the body portion to provide an annular shoulder 19 which will bear against the outer end of each leg. A hole 20 is provided in the foot and extends through its entire length. This hole is enlarged in the knob at 21, as clearly shown in the drawings and particularly in Fig. 6 thereof.

A washer 22 is embedded in the knob where the enlargement 21 begins, and provides a bearing for a bolt 23. The bolt passes through the hole in the foot with its head 24 bearing against the washer 22. A washer 25 fits over the threaded end 26 of the bolt to form a bearing for the nut 27.

The washer 25 is substantially as large in diameter as the inner end of the body portion, and it has a plurality of lugs 28 struck up therefrom which engage the nut 27 and prevent the nut from turning when the bolt 23 is being tightened.

In practice the bolt 23 is arranged in the hole 19 with the bolt head 24 bearing against the washer 22 and the threaded bolt end 26 extended through the inner end of the body portion. The washer 25 is then arranged on the end of the bolt and the nut screwed on until it seats within the lugs 28. The parts are then in proper assembled position and the body portion of the foot is inserted into the

tubular leg 11 until the outer end of the leg bears against the annular shoulder 19. A screw driver or other implement is then arranged in the slot 29 in the bolt head 24 and the bolt tightened. The lugs 28 prevent the nut from turning so when the bolt is turned the rubber between the washers 22 and 25 will be compressed and swell out against the inside of the leg and firmly secure the foot 10 in position on the leg.

10 The invention provides a foot for chair legs and the like which is securely maintained in position and which can be readily and quickly assembled. The knob has its 15 outer periphery flush with the outside of the leg and presents a finished and neat appearance. The foot is simple in construction, efficient in use, and can be readily and economically manufactured.

20 Changes may be made in the form, construction, and arrangement of the parts without departing from the spirit of the invention or sacrificing any of its advantages, and the right is hereby reserved to make all such 25 changes as fairly fall within the scope of the following claim.

The invention is hereby claimed as follows:

A furniture foot consisting of the leg of a 30 chair or the like, having a cylindrical bore, a resilient cushion member having a cylindrical shank fitting into said bore, the head at the outer end of the shank being of greater diameter than the shank proper, whereby it 35 may abut the end of the chair leg, a washer abutting the inner end surface only of the shank of the resilient member and covering substantially the entire inner end surface, a screw extending axially through the resilient 40 member, and a nut for the inner end of the screw, the washer having projections to prevent the nut from rotating when the screw is rotated, and the washer making inner end surface contact only with the shank portion 45 of the resilient member, whereby when the screw is tightened, the shank portion is compressed longitudinally, whereby the shank expands within the leg substantially uniformly throughout its length, the outer end 50 of the resilient member being countersunk to accommodate the head at the outer end of the screw.

In witness whereof, I have hereunto subscribed my name.

JAMES E. BALES.
